2 SHEETS—SHEET 2.

Inventor,

George W. Dy Arman,
By Frederick V. Winter,
Attorney.

UNITED STATES PATENT OFFICE.

GEORGE W. DY ARMAN, OF NEW YORK, N. Y.

REINFORCED ROAD CONSTRUCTION.

Application filed May 23, 1921. Serial No. 471,583.

To all whom it may concern:

Be it known that I, GEORGE W. DY ARMAN, a citizen of the United States, residing at New York, in the county and State of New York, have invented certain new and useful Improvements in Reenforced Road Constructions, of which the following is a full, clear, and exact specification.

This invention relates to pavement or road construction and has for its object to provide a durable surface for roadways which may be easily laid and is capable of resisting the formation of ruts even under heavy traffic. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts in the several views:

Figure 1 is a plan view of a portion of a road constructed substantially in accordance with this invention.

Figure 2 is a side view of the same, partly in section.

Figure 3 is a section on the line III—III of Figure 1.

Figure 4 is a similar section showing a modified form of lateral supporting members.

Figure 5 is a section on the line V—V of Figure 1.

Figure 6 is a side view of a modified form of paving or surface member.

Figure 7 is an end view of the same.

Figure 8 is a broken inner face view of the form of lateral supporting member illustrated in Figures 1 and 3.

Figure 9 is a side view of one end portion of the modified form of paving or surface member.

Figure 10 is a side view, partly in section, of a modified form of road or pavement.

Figure 11 is a section on the line XI—XI of Figure 10.

Figure 12 is a plan view of the road or pavement shown in Figures 10 and 11.

Figure 13 is a detailed perspective view of one of the spacing members used in said pavement.

Figure 14 is a detailed perspective view of one of the paving blocks used in said pavement.

Figure 15 is a detailed perspective view of one of the wedge-shaped key members of said pavement.

Referring first to Figures 1 and 3, 1 designates foundation members which are preferably formed of stone, concrete, or other suitable material, and placed at intervals along the road to be paved. One or more intermediate foundation members 2 may be placed between adjacent foundation members 1, permitting the latter to be placed farther apart than would otherwise be possible when constructing a durable pavement.

Each of the foundation members 1 has oppositely extending recesses 3 in its upper surface, the side walls 4 and end walls 5 of said recesses being preferably inclined. The intermediate foundation members 2 have recesses 6 in their upper surfaces and extending across said members, the lateral walls 7 as well as the bases of said recesses 6, corresponding to the similar parts of the recesses 3 in the foundation members 1. Between adjacent foundation members 1, lateral supporting members 8 are arranged in engagement with the side walls 4 and 7, respectively, of the members 1 and 2. These supporting members 8 may be made of cast iron, steel, or other suitable material and are preferably provided with longitudinal ribs 9 on their inner faces to interlock with

concrete surface members 10 constituting the main part of the pavement and extending longitudinally between adjacent foundation members 1 and laterally between the supporting members 8. Said surface members 10 are formed by pouring concrete in the usual manner, so that the lateral edges thereof conform to the inner faces of the supporting members 8. Reinforcing metal rods 11 may be used in said surface members for strengthening the same. Reinforcing rods 12 may also be used in the formation of the foundation members 1, as shown in Figures 4 and 5, when said members are made of concrete.

To further lock or connect the surface members 8 to the foundation members 1 and 2, tie bolts 13 may be employed, the lower end of each of said bolts being embedded 5 in said foundation members, while their upper ends are embedded in said surface member, as best shown in Figures 2 and 4. It will be understood that the pavement may be made of any width desired and will in 10 practice be made much wider in proportion to its other dimensions than indicated by the accompanying drawings.

In place of the cast metal supporting members 8, shown in Figures 1, 3 and 8, 15 sheet metal members 14, Figure 4, may be used. The ribs 15 on said members 14, corresponding to the ribs 9 on the members 8, may be formed by bending the middle portion of said members 14 into the form of inwardly extending beads, as shown in Figure 20 4. Said beads 9 and 15 may be omitted, if desired, and the surface members 10 formed with smooth inclined lateral faces 16, as shown in Figures 6 and 7, the incline of 25 said faces serving to support said surface members and the bolts 13 serving to anchor them to the foundation members. The ends of the surface members 10 may be stepped, if desired, to prevent the upper edge thereof 30 from chipping off, said stepped formation being indicated at 17 in Figure 9.

Referring now to Figures 10 to 15 of the drawings, the foundation 20 for the pavement may be made continuous and with a 35 succession of arches 21, said foundation being preferably supported on cross pieces 22 arranged between the arches. Said foundation 20 has a continuous groove or recess 23 formed in its upper surface to receive paving 40 blocks 24 arranged in transverse rows, as best illustrated in Figure 12. Between each transverse row of the paving blocks 24, spacing members 25 are preferably arranged, the latter terminating slightly below 45 the surface of the former. The blocks 24 may be made of concrete, wood, or any other suitable material, and the spacing members 25 may be made of metal or other durable substance.

50 Each spacing or separating member 25 has perforations 26 therein for the passage of screws 27, Figure 10, which serve to fasten said member to the paving blocks of the adjacent transverse row. The heads 28 of 55 the screws 27 project beyond said spacing member and engage sockets 29 formed in the blocks 24 of the row at the other side of said member 25. At intervals along the foundation 21, wedge-shaped key members 60 30 are inserted between adjacent rows of paving blocks 24 instead of spacing members 25. When said key members are removed, the paving blocks may be readily adjusted with their sockets 29 engaging the 65 heads 28 of the screws 27, and when said

key members are put in place, they hold said blocks and spacing members compactly together so that the heads of the screws interlock with the notches 29.

The key members 30 preferably extend 70 through the sides of the foundation 20 in which corresponding notches 31 are formed, as shown in Figure 10. To retain said key members in position longitudinal rails 32 are embedded in notches 33 in said key members, said rails also fitting in corresponding notches 34 in the end paving blocks of each 75 row and in similar notches 35 in the spacing members 25. The rails 32 may be fastened in any suitable manner, as by screws 80 36, Figure 12, arranged at intervals along the same and engaging into certain of the paving blocks which are held together by the screws 27, as already explained.

I claim:

1. In a pavement, the combination with spaced foundation members extending across the pavement, of lateral supporting members extending between and supported on said foundation members, and plastic 90 surface members also extending between and supported at their ends on said foundation members, the lateral edges of said surface members being supported on said lateral supporting members.

2. In a pavement, the combination with spaced foundation members extending across the pavement, of lateral supporting members extending between and supported on said foundation members, and plastic 100 surface members also extending between and supported at their ends on said foundation members, the lateral edges of said surface members being supported on said lateral supporting members, there being longitudinal 105 ribs on the inner lateral faces of said lateral members interlocked with the lateral edges of said surface members for the purpose specified.

3. In a pavement, the combination with 110 spaced foundation members extending across the pavement, of lateral supporting members extending between and supported on said foundation members, plastic surface members also extending between and supported at their ends on said foundation members, the lateral edges of said surface members being supported on said lateral supporting members, and means for anchoring 115 said surface members at their ends to 120 the foundation members.

4. In a pavement, the combination with spaced foundation members extending across the pavement, of lateral supporting members extending between and supported on 125 said foundation members, plastic surface members also extending between and supported at their ends on said foundation members, the lateral edges of said surface members being supported on said lateral 130 members.

supporting members, and means for anchoring said surface members to said lateral supporting members.

5. In a pavement, the combination with 5 spaced foundation members extending across the pavement, of lateral supporting members extending between and supported on said foundation members at the lateral edges of the pavement, plastic surface members 10 also extending between and supported at their edges on said foundation members, the lateral edges of said surface members being supported on said lateral supporting members, means for anchoring said surface 15 members at their sides to said lateral supporting members, and means for anchoring said surface members at their ends to said foundation members.

6. In a pavement, the combination with 20 spaced foundation members, of lateral supporting members extending between said foundation members, plastic surface members also extending between and resting on said foundation members and engaging said 25 lateral supporting members, and tie bolts having offsets at both ends one end embedded in said foundation members and the other end embedded in said surface members.

30 7. In a pavement, the combination with a foundation having a groove therein, of paving blocks arranged in said groove, spacing member arranged transversely between said blocks, bolts securing each spacing 35 member to the blocks at one side thereof and having their heads projecting at the other side thereof, the paving blocks at the other side of each of said spacing members having notches to engage the heads of said

bolts, transverse key members for retaining 40 the blocks and spacing members compactly together, and means for retaining said key members in position.

8. In a pavement, the combination with a foundation having a groove therein, of 45 paving blocks arranged in said groove, spacing members arranged transversely between said blocks, bolts securing each spacing member to the blocks at one side thereof and having their heads projecting at the 50 other side thereof, the paving blocks at the other side of each of said spacing members being notched to engage the heads of said bolts, and transverse key members for retaining the blocks and spacing members 55 compactly together.

9. In a pavement, the combination with a foundation having a groove therein, of paving blocks arranged in said groove, spacing members arranged transversely between 60 said blocks, bolts securing each spacing member to the blocks at one side thereof and having their heads projecting at the other side thereof, the paving blocks at the other side of each of said spacing members 65 being notched to engage the heads of said bolts, transverse key members for retaining the blocks and spacing members compactly together, and strips extending longitudinally of the groove in the foundation 70 and across the key members and adjacent paving blocks, said strips being embedded in said key members and blocks and secured to the latter for the purpose specified. 75

In testimony whereof I have signed my name to this specification.

GEORGE W. DY ARMAN.
